UNITED STATES PATENT OFFICE.

HARRY H. SCHROYER, OF CHICAGO, ILLINOIS, ASSIGNOR, BY MESNE ASSIGNMENTS, TO
PROTECTO MANUFACTURING COMPANY, A CORPORATION OF ILLINOIS.

EXTENDING-BRACKET FOR AWNINGS.

1,274,945.

Specification of Letters Patent.

Patented Aug. 6, 1918.

Original application filed November 26, 1915, Serial No. 63,527. Patent No. 1,243,988. Divided and this application filed September 20, 1917. Serial No. 192,333.

To all whom it may concern:

Be it known that I, HARRY H. SCHROYER, a citizen of the United States, and a resident of the city of Chicago, in the county 5 of Cook and State of Illinois, have invented certain new and useful Improvements in Extending-Brackets for Awnings; and I do hereby declare that the following is a full, clear, and exact description of the same, 10 reference being had to the accompanying drawings, and to the numerals of reference marked thereon, which form a part of this specification.

This invention is a division of my allowed 15 application for patent for improvements in an "Awning", filed Nov. 26, 1915, Serial No. 63,527, which became Patent No. 1,243,988, October 23, 1917, and relates to an improved form of an extending bracket for an awning fabric and the method of mounting the 20 same whereby said bracket when in lowered horizontal position is prevented from sliding upwardly in the guides provided therefor, but is capable of swinging downwardly.

It is an object of this invention to provide an improved form of an awning fabric extending bracket which when in horizontal position is prevented from being raised upwardly.

It is also an object of this invention to construct an awning wherein the fabric is connected to an extending bracket slidably engaged in suitable guides having means 35 therein for preventing elevation of the bracket when the same is in a horizontal position.

It is furthermore an object of this invention to provide an awning the lower end of 40 the fabric of which is connected to an extending bracket having segment shaped gudgeon heads formed thereon adapted to slidably engage in window frame guides provided with means for preventing the elevation 45 of said bracket when in a horizontal position but permitting the bracket to swing either upwardly or downwardly from horizontal position.

It is an important object of this invention 50 to construct a simple and effective type of an awning fabric extending bracket easy to operate and adapted when in an extended horizontal position from being elevated by

projecting means secured within the bracket guides. 55

Other and further important objects of this invention will be apparent from the disclosures in the drawings and specification.

The invention (in a preferred form) is illustrated in the drawings and hereinafter 60 more fully described.

On the drawings:

Figure 1 is a central vertical section taken through a window showing the same equipped with an awning provided with an 65 extending bracket construction embodying the principles of this invention.

Fig. 2 is a fragmentary enlarged sectional detail taken on line 2—2 of Fig. 1.

Fig. 3 is an enlarged detail sectional view 70 with parts omitted, taken on line 3—3 of Fig. 2.

Fig. 4 is a section taken on line 4—4 of Fig. 3.

As shown on the drawings: 75

The reference numeral 1, indicates as a whole a window frame, in which are slidably mounted the upper and lower window sashes 2 and 3, respectively. Secured in any suitable manner upon the upright side members of the frame 1, are angle irons 4, which have brazed, riveted or secured thereto in any suitable manner guide channels 5. Mounted at the upper end of the window frame on each side thereof are brackets 6, 85 which receive detachably engaged therein the gudgeon ends of a spring roller 7, to which the upper edge of an awning fabric 8, is attached and adapted to be wound thereon. Connected at the other or lower end of 90 the fabric 8, is a U-shaped extending bar or bracket 9, having rigidly secured on the ends of the inwardly directed arms thereof end caps 10, each of which has integrally formed on the outer side thereof a longitudinal or rearwardly projecting flange or projection 11, the end of which is rounded.

Formed at right angles on the outer surface of each of the flanges 11, is a stub shaft or neck piece 12, on the end of each of which 100 is integrally formed a gudgeon head 13, disposed in a plane parallel to the plane of the flanges 11. Each of said gudgeon heads 13, has one side thereof cut away to afford a flat surface 14, and leave a head of segment 105 shape, as clearly shown in Fig. 3.

The segment shaped gudgeon heads 13, fit within the channel guides 5, and are adapted to slide therein when the awning is raised or lowered. Rigidly secured within each of 5 said guide channels 5, near the lower end thereof is a Z- or angle-shaped stop or locking bracket 15, having integrally formed at right angles to the upper portion thereof a horizontal stop or projection 16, beneath 10 which one end of the flat surface 14, of one of the segment heads 13, projects when the U-shaped extending bracket 9, is swung downwardly into a horizontal position as shown in Fig. 3. Due to the shape of the 15 gudgeon heads 13, and the positions of the projections 16, elevation of the gudgeon heads 13, in the guide channels 5, is prevented with the bracket 9, in extended horizontal position for use, or even if the bracket 9, is 20 swung downwardly below a horizontal position.

A controlling and actuating cord 17, is connected at one of its ends to cords 18, which are attached around the roller 7, and 25 at its other end extends through a small pulley 19, secured on the window-sill, and with the other end adapted to be engaged over a hook 20, provided on the extending bracket 9, as shown in Fig. 1, and then attached to 30 any suitable fastening means on the window-sill. Said cord 17, thus serves to hold the awning extended, and even accidental release of the spring in the roller 7, to rotate the roller, will be resisted by the cord which is 35 attached around the hook 20. Movable secured to one side of the window-frame 1, in one end of a cross rod 21, the other end of which is adapted to be removably seated in a hooked member 22, mounted upon the op- 40 posite side of the window-frame, to permit said cross rod 21, when in horizontal position to confine the upper portion of the awning fabric 8, substantially in the plane of the window-frame, while the lower portion of 45 said fabric is held extended outwardly away from the window by the bracket 9.

The operation is as follows: The guide channels 5, are first attached to the side frame members of the window, and then to 50 the brackets 6, in which the roller 7, is detachably journaled. The segment shaped gudgeon heads 13, of the extending bracket 9, are then engaged through the open upper ends of the guide channels, within which the 55 gudgeon heads subsequently operate during the elevating and lowering movements of the awning. The spring within the curtain roller 7, serves to wind the awning fabric 8, thereon when it is desired to elevate the awning in a usual and well known manner, the 60 cord 17, is pulled downwardly, thus rotating the curtain roller 7, against the stress of its internal spring. The ends of the extending bracket 9, are adapted to slide downwardly 65 by gravity in the guides 5, the gudgeon heads

13, of which finally strike the stop brackets 15, therein, thereby permitting the bracket 9, to swing outwardly into a substantially horizontal position after which the cord 17, is engaged over the hook 20, on said bracket 9, 70 and fastened to the window-sill to hold the awning in extended position, after which the cross rod 21, is swung upwardly into a horizontal position across the front of the awning fabric and seats in the hooked member 75 22, to confine the upper portion of the awning fabric in the plane of the window-frame.

The shape of the gudgeon heads 13, is such that when the extending bracket 9, is swung downwardly into horizontal position to extend the lower portion of the fabric away from the window, the flat surfaces 14, of said gudgeon heads are disposed to extend beneath the stops 16, of the stop brackets 15, thus preventing the inner ends of the bracket 80 9, from being forced upwardly by accident or otherwise within the guide channels to invert the extending bracket.

I am aware that numerous details of construction may be varied through a wide 90 range without departing from the principles of this invention, and I therefore do not purpose limiting the patent granted otherwise than necessitated by the prior art.

I claim as my invention:

1. The combination with a guide channel, of a stop therein, an extending bracket, and a segment shaped gudgeon head thereon adapted to slide in said guide channel and extend beneath said stop when said extending bracket is in horizontal position to hold said extending bracket from being raised upwardly.

2. The combination with a guide channel, of an angle locking means therein, an extending bracket, and a gudgeon head thereon adapted to engage in said guide channel and having portions thereof cut away to afford a flat surface to permit said gudgeon head to pass the stop when the bracket is in a vertical position and to contact said stop when said bracket is in horizontal position.

3. The combination with a channeled guide, of an angle shaped bracket therein, a horizontal stop integrally formed at right angles to the upper portion thereof, an extending bracket, and a gudgeon head secured to the end of said bracket provided with a flat surface adapted to contact said stop when said extending bracket is in horizontal position.

4. The combination with a channeled guide, of locking means therein, an extending bracket, and segment shaped means formed thereon and slidably engaged in said guide to pass said locking means when said bracket is in vertical position and adapted to contact said locking means to hold said extending brackets from being elevated when in an extended horizontal position for use.

5. The combination with channeled guides, of stops therein, an extending bracket, an end cap secured on each end thereof, a flange integrally formed on each cap, a stub shaft 5 rigidly secured on each flange at right angles thereto, and a segment shaped head integrally formed on each of said stub shafts engaged in said guides and adapted to engage said stops when said bracket is in extended 10 horizontal position to hold the same against upward movement.

6. The combination with a guide channel, of a stop therein, an extending bracket, and

a segment shaped head thereon adapted to pass said stop when the bracket is in a vertical position and contact said stop when said bracket is in a horizontal position to hold said bracket from elevation in said guide channel.

In testimony whereof I have hereunto subscribed my name in the presence of two subscribing witnesses.

HARRY H. SCHROYER.
